UNITED STATES PATENT OFFICE.

CHARLES T. BEERS, OF NORWALK, CONNECTICUT, ASSIGNOR TO GEO. H. RAYMOND, 2D, OF SAME PLACE.

FURNACE-GRAVE.

SPECIFICATION forming part of Letters Patent No. 240,949, dated May 3, 1881.

Application filed January 7, 1881. (Model.)

To all whom it may concern:

Be it known that I, CHARLES T. BEERS, of Norwalk, in the county of Fairfield and State of Connecticut, have invented a new Improvement 5 in Furnace-Grates; and I do hereby declare the following, when taken in connection with the accompanying drawings and the letters of reference marked thereon, to be a full, clear, and exact description of the same, which 10 said drawings constitute part of this specification, and represent, in—

Figure 1, a top view; Fig. 2, a sectional front view; Fig. 3, a sectional side view from one side; Fig. 4, a sectional side view from the opposite 15 side.

This invention relates to an improvement in grates, especially adapted to furnaces for heating purposes, also applicable to other purposes, the object being to apply to the grate either 20 a tipping or a shaking movement, or both; and the invention consists in the construction as hereinafter described, and particularly recited in the claims.

A represents the grate, which is circular in 25 form and provided with the usual openings for draft and for the passage of ashes.

Below the grate and across the ash-pit B is a shaft, C. The shaft has a bearing at each 30 side, upon which it may be oscillated. This shaft extends diametrically across the grate-opening, and the grate is provided with a central stud, D, which fits into a corresponding seat in the shaft C, so that the grate may be rotated in a horizontal plane, with said stud D 35 as its center of rotation. The shaft C, being permitted to rotate, tips the grate from its horizontal plane, as for the purpose of dumping, &c., and as seen in broken lines, Fig. 4.

For the purpose of tipping the grate, an arm, 40 E, extends down from the shaft C below the pivot, and from this arm a connecting-rod, F, is jointed to a rocking lever, G. The pivot *g* of the lever G extends through the case to the outside, and is fitted for the application of a 45 crank or lever, as in the usual manner, for shaking or dumping the grate, so that a crank or lever applied thereto will turn the lever G, as seen in broken lines, Fig. 4, to tip the grate.

To shake the grate a rocking lever, H, is ar-

ranged within the ash-pit, its pivot *h* extending outside for the application of the crank or lever thereto, as before described, so as to vibrate the said lever, and from the opposite end of the lever H a connecting-rod, I, extends to and in connection with the grate, here represented as by a trunnion, *i*, on the grate, resting in a loop or eye, L, on the end of the connecting-rod I, and so that by turning the lever H up and down, as indicated in broken lines, Fig. 3, a rotating or oscillating movement will 60 be imparted to the grate and in its own plane, which will disturb the fire upon it so as to cause the ashes to fall through the grate.

The grate can be oscillated after it is tipped, if it is found desirable so to do, in order to 65 clear the clinkers and ashes therefrom.

I am aware that fire-grates have been arranged so as to be rotated and oscillated in their horizontal plane, and also so as to be tipped for the purpose of dumping. 70

I claim—

1. A furnace-grate arranged upon a horizontal shaft beneath it, a rigid arm, E, extending downward from said shaft, and a rocking lever, G, connected by a rod, F, to the said arm 75 E, substantially as and for the purpose described.

2. A furnace-grate pivoted to a horizontal shaft beneath it, and adapted to be turned on said pivot in a horizontal plane, combined with 80 a rocking lever, H, and a rod, I, connecting said lever directly to the grate, whereby a rotary motion in a horizontal plane may be imparted to said grate, substantially as described.

3. A furnace-grate arranged upon a horizontal shaft beneath it, an arm, E, extending downward from said shaft, a rocking lever, G, connected by a rod, F, to said arm E, whereby the grate is tipped, combined with a rocking lever, H, and a rod, I, connecting said lever 85 H directly to the grate, whereby the grate may be rotated upon its pivot, all substantially as described.

CHARLES T. BEERS.
